Witnesses. k l m n o z Inventor;

Alfred H. Daehler
S. L. Jordan.

Armand G. Miss,
by Raymond Lee Blakely,
his attorney.

UNITED STATES PATENT OFFICE.

ARMAND GINSS, OF DOWNEY, CALIFORNIA, ASSIGNOR OF ONE-HALF TO CHARLES BARRINGTON, JR., OF LOS ANGELES, CALIFORNIA.

RAILWAY-TRANSFER.

1,137,398.

Specification of Letters Patent.

Patented Apr. 27, 1915.

Application filed November 14, 1913. Serial No. 801,042.

To all whom it may concern:

Be it known that I, ARMAND GINSS, a citizen of the United States, residing at Downey, in the county of Los Angeles and State of California, have invented new and useful Improvements in Railway-Transfers, of which the following is a specification.

This invention relates to an improved railway transfer which comprises a railway transfer ticket, such transfer tickets or transfers, as they are called, being issued to passengers of street railway, or urban or suburban railway cars, for the purpose of enabling passengers to change from line to line, or branch to branch, or route to route, of the railway service. In order that such transfers may be properly validated for use, and to prevent improper issuance and use thereof, numerous schemes and systems of provision and arrangement of printed matter, spaces for punching, and the like, have been devised.

The present invention aims at providing more complete protection for the railway by more effectually preventing improper issuance and unwarranted use of such transfers.

Further objects of the invention are to provide an improved railway transfer in which a large number of factors and a large amount of data pertinent to car route, time of transfer, day, month, year, together with direction of motion of the car upon which the transfer is issued and the direction of motion of the car to which the transfer is made, further together with the route number of the car upon which the transfer is issued, and the consecutive number of the transfer, all may be arranged upon a relatively small surface, and the use of and reference to which will be convenient and simple, as shall also be the final checking over and tallying of the surrendered and returned transfers.

A further particular object is the provision of an improved railway transfer which will be "universal" in its applicability to and use upon an entire system of railway routes and each of the same, obviating the necessity of specially producing and printing particular and separate transfers for the several separate routes or branches of the system; and it also aims at providing a railway transfer which will permit of the adoption and use of simple rules governing the use of such transfers, thus rendering the is-

suance, inspection, validity, surrendering, returning and checking of the transfers exceedingly simple and accurate.

With the above and other objects in view, including relatively increased efficiency, the invention consists of the novel and useful provision, formation, combination and relative arrangement of parts, members and features, all as hereinafter described, shown in the drawing, and finally pointed out in claims.

The drawing is a face view of a railway transfer ticket formed, produced and printed in accordance with the invention.

Referring with particularity to the drawing, in which reference characters are utilized to indicate certain features of the invention, Y designates a suitable rectangular paper blank upon which is displayed or disposed various data and readings, and upon which various spaces are marked off or laid out, in practising the invention. The blank Y is preferably of considerably greater length than width. At the top X thereof is provided the following reading, transversely arranged: "Los Angeles Railway. Good only if presented within 15 minutes of time and in direction punched." The space directly beneath this heading is ruled off vertically to produce a wide column a in which are consecutively arranged the various headings or names of the routes or lines of the railway system, and two narrow right-hand columns b and c, in which, opposite each route named, are arranged respectively the initial letters of the two main directions in which the cars of the respective routes travel.

In the column a, at the bottom, is left a blank space within which, at the left, a vertical series of capital letters is arranged, to designate new routes or lines prior to the inclusion of the names thereof in the column above, which inclusion takes place when the next batch of fresh transfers are printed. The coinciding spaces in the columns c and b are likewise left blank for the filling in of the direction initial letters as may be proper. A line is drawn transversely of the blank Y beneath the columns a, b and c, and the space immediately beneath the same at the left is blocked off into a column of twelve spaces d each printed with the name of a calendar month, or an abbreviation thereof, in a consecutive series. At the right of this

column is blocked off a space *e* in which is printed in distinguishing color the date of the month. At the right of the column *e* are blocked off five vertical spaces *f* marked respectively "North", "South", "East", "West", and "Stop"; to the right of these five spaces are blocked off five further spaces *g* in the uppermost of which appears the reading, "A". "M".; and to the right of these five spaces is a vertical column of five other blocked off spaces *h* registering therewith respectively and with the respective spaces *f*, and the uppermost of which bears the reading "P". "M". In a rectangular space beneath the spaces *e*, *f*, *g*, *h*, is a left-hand vertical column *k* for the consecutive number of the transfer. Next to the same at the right is a similar column *l* for the serial number of the trip of the car to whose conductor the transfers are issued. To the right of the column *l* are four vertical columns *m*, *n*, *o*, *p*, all divided transversely into twelve transverse columns within which and within the column *m* appear hour numbers from 1 to 12, respectively, arranged consecutively from 1 at the top to 12 at the bottom. In the uppermost of such transverse columns, and within the respective vertical columns *n*, *o*, *p*, are arranged, from left to right the numbers "15", "30", "45", relating to minutes of the hour.

It will be understood that the several spaces and columns are blocked off by suitable lines and rulings; and the several spaces *h* for the "P". "M". readings are preferably shaded so they may be readily distinguished from the spaces *g* of the "A". "M". readings. The consecutive ticket number in the column *k* and the serial car trip or run number in the column *l* are preferably in a distinguishing color similar to the date reading in the space *e*.

In using the transfer, the issuing conductor punches the transfer in the column *b* or *c* opposite the name of the route his car is traversing, in accordance with the direction of motion thereof. He then makes a punch in one of the spaces *g* or *h* in accordance with the half day of the time of issuance, and in registration with the proper space *f* to indicate the direction in which the passenger wishes to travel upon the connecting or intersecting route. If the route of the car is blocked or the trip interrupted, the conductor also punches the space *f* printed "Stop", and the passenger is then permitted to travel upon the next convenient or parallel line. The proper space *d* is punched to designate the current month, or all the blanks may be punched at once when first received by the conductor in such proper space *d*. The proper transverse column in the proper vertical column *m*, *n*, *o* or *p* is also punched to designate the hour or quarter-hour closest to which the transfer is

issued. Thus, ordinarily, but three punches are required, and the punch is passed along the blank in making these punches, the punching operation thus being simple and convenient.

When the transfer is presented to the conductor of another car, he examines it to determine whether more than fifteen minutes has elapsed since the transfer was issued, and whether the direction in which his car is traveling tallies with the direction punched in one of the spaces *f*, *g* or *h*. If he does not find these conditions satisfactory to his inspection he is to refuse the transfer.

It will be noted that the invention permits of the use of a universal transfer for all the routes or lines of a railway system, is compact or condensed in form, is simple and easy in its use and issuance and inspection on surrender, and may be readily checked up or tallied in the office of the auditor of the railway. The rules pertinent to its use will consist more in a few simple exceptions rather than in regulations for current use, as the transfer will readily fit almost every conceivable combination of circumstances to be met with in any transfer of passengers.

Having thus described my invention I claim and desire to secure by Letters Patent:

1. A railway transfer comprising a blank provided upon its face with a single tabular list of the several routes, including the route upon which the transfer is to be issued, also with spaces in alinement with each name of the list containing characters for designating the direction in which an issuing car is traveling upon the route, and also with spaces containing characters indicating the direction in which the car upon which the transfer may be validly used is to travel.

2. A railway transfer comprising a blank provided upon its face with a tabular list of the several routes, including the route upon which the transfer is to be issued, also with spaces in alinement with each name of the list containing characters for designating the direction in which an issuing car is traveling on the route, also with spaces containing characters for indicating the direction in which the car upon which the transfer may be validly used is to travel, and also with A. M. and P. M. indicating spaces having a zone relation with the last mentioned spaces so that the half of the day together with the direction of the car upon which the transfer may be used can be indicated by a single operation.

3. A railway transfer comprising a blank provided upon its face with a tabular list of the several routes, also with spaces in alinement with each name of the list containing characters for designating the direction in which an issuing car is traveling on the route, also with a column of spaces containing characters for indicating the direc-

tion in which the car upon which the transfer may be validly used is to travel, and also with parallel columns of A. M. and P. M. spaces arranged transversely in zones with 5 the spaces of the first mentioned column so that the half of the day and the direction of the car upon which the transfer may be used can be indicated by a single operation.

4. A railway transfer comprising a blank 10 provided upon its face with a column of spaces containing characters for indicating the direction in which the car upon which the transfer may be validly used is to travel, and also with parallel columns of A. M. and 15 P. M. indicating spaces arranged in transverse zones with the direction indicating spaces of the first mentioned column so that both the half of the day and the direction of the car upon which the transfer may be 20 used can be indicated by a single operation.

5. A railway transfer comprising a blank provided upon its face with a column of spaces containing characters for indicating the direction in which the car upon which 25 the transfer may be validly used is to travel, also with parallel columns of A. M. and P. M. indicating spaces arranged in transverse zones with the direction indicating spaces of the first mentioned column so that 30 both the half of the day and the direction of the car upon which the transfer may be used can be indicated by a single operation, and also with a series of parallel columns divided into twelve identified transverse 35 zones so that a fractional part of the hour of the day can be indicated by a second operation.

6. A railway transfer comprising a suitable blank provided upon its face with a 40 tabular list of the names of the several

routes of the railway, with identified spaces in registration with each name for designating either of two directions in which a given issuing car is traveling on a route, and a space designating the direction in which a 45 car upon which the transfer may be validly used is to travel, together with identified spaces in registration with said last named space and whereby the half of day in which the transfer is issued may be designated by 50 a single operation also designating said last named direction.

7. A railway transfer comprising a suitable blank provided upon its face with a tabular list of the names of the several 55 routes of the railway, with identified spaces in registration with each name for designating either of two directions in which a given issuing car is traveling on a route, and an identified space designating the direction 60 in which a car upon which the transfer may be validly used is to travel, together with identified spaces in registration with said last named space and whereby the half of day in which the transfer is issued may be 65 designated by a single operation also designating said last named direction; said suitable blank being further provided upon its face with four parallel identified columns divided into twelve identified transverse zones 70 within any of which by a single operation a quarter hour of the day may be designated.

In testimony whereof, I have signed my name to this specification in the presence of two subscribing witnesses.

ARMAND GINSS.
